UNITED STATES PATENT OFFICE

MARTIN J. GOULOOZE, OF GRAND RAPIDS, MICHIGAN, ASSIGNOR TO KELVINATOR CORPORATION, OF DETROIT, MICHIGAN, A CORPORATION OF MICHIGAN

DESIGN FOR A DRINKING WATER COOLER

Application filed April 29, 1933. Serial No. 47,941. Term of patent 14 years.

To all whom it may concern:

Be it known that I, MARTIN J. GOULOOZE, a citizen of the United States, residing at Grand Rapids, in the county of Kent, State of Michigan, have invented a new, original, and ornamental Design for a Drinking Water Cooler, of which the following is a specification, reference being had to the accompanying drawing, forming part thereof.

The figure is a perspective view of a drinking water cooler showing my new design.

I claim:

The ornamental design for a drinking water cooler as shown.

MARTIN J. GOULOOZE.
